CLAIM

The ornamental design for footwear with grid pattern, as shown and described.

DESCRIPTION

FIG. 1 is a rear elevational view of footwear with grid pattern, showing my new design.

FIG. 2 is a left side elevational view thereof.

FIG. 3 is a right side elevational view thereof; and,

FIG. 4 is a left side elevational view thereof, shown in an alternate environment.

The broken lines portions of FIGS. 1-4 are included to show unclaimed subject matter in use only and form no part of the claimed design.

1 Claim, 4 Drawing Sheets
